UNITED STATES PATENT OFFICE.

MORRIS SCHLEPP, OF NEW YORK, N. Y.

DESIGN FOR A LIGHTING-FIXTURE ROSETTE.

Application filed May 12, 1927. Serial No. 21,945. Term of patent 3½ years.

To all whom it may concern:

Be it known that I, MORRIS SCHLEPP, a citizen of the United States, and a resident of New York city, borough of Manhattan, in the county and State of New York, United States of America, have invented a new, original, and ornamental Design for a Lighting-Fixture Rosette, of which the following is a specification, reference being had to the accompanying drawing forming part thereof.

Figure 1 is a plan view of a lighting fixture rosette showing my new design.

Fig. 2 is an edge view thereof.

I claim:

The ornamental design for a lighting fixture rosette, substantially as shown.

MORRIS SCHLEPP.
